UNITED STATES PATENT OFFICE

BENJAMIN NATHAN, OF NEW YORK, N. Y., ASSIGNOR TO FOREMOST FABRICS CORPORATION, OF NEW YORK, N. Y., A CORPORATION OF DELAWARE

DESIGN FOR A TEXTILE FABRIC

Application filed January 5, 1931. Serial No. 38,196. Term of patent 3½ years.

To all whom it may concern:

Be it known that I, BENJAMIN NATHAN, a citizen of the United States, residing at 222 West 83d Street, city of New York, county of New York, and State of New York, whose post-office address is 392 Fifth Avenue, city of New York, county of New York, and State of New York, have invented a new, original, and ornamental Design for a Textile Fabric, of which the following is a specification, reference being had to the accompanying drawing, forming part thereof.

The figure is a plan view of a textile fabric showing my new design. A single unit of my design is substantially comprised within the area defined by the indicating lines shown on the drawing.

I claim:

The ornamental design for a textile fabric substantially as shown and described.

BENJAMIN NATHAN.
